RAILWAY SWITCH OPERATING APPARATUS

George W. Baughman, Swissvale, Pa., assignor to
The Union Switch & Signal Company, Swiss-
vale, Pa., a corporation of Pennsylvania

Application March 17, 1948, Serial No. 15,373

19 Claims. (Cl. 246—393)

1

My invention relates to railway switch operating apparatus, and particularly to apparatus for manually operating a spring switch.

In switch operating apparatus of the type described, the switch is connected to a hand-throw lever through a suitable spring biasing means which normally holds the switch in the position selected by the hand-throw lever, but which yields to permit trailing of the switch by a train.

It sometimes becomes necessary for a train which is trailing a switch of this type to stop and back up. This necessitates reversing the switch so that it will not be split by the train. At such times, the switch points may be held in their trailed position by the wheels of a vehicle stopped on the switch. When this happens, the spring biasing means in the switch mechanism applies a force to the hand-throw lever, tending to move it to its reverse position.

Under such conditions, a switchman operating the hand-throw lever must be careful to apply to the lever a force opposing the spring, in order that he may retain control of the lever and prevent it from moving suddenly to its reverse position. Switch operating mechanisms commonly provide a sufficient mechanical advantage between the hand-throw lever and the switch so that a switchman may readily retain control of the switch with the spring biasing force acting on it. If the switchman does not retain control of the switch, the resulting sudden movement of the switch may damage the switch operating mechanism or even, conceivably, injure the switchman if he is so careless as to leave some part of his body in the path of the moving lever.

It is desirable to provide means to insure that the switchman will retain control of the switch, and one object of my invention is to provide novel means for this purpose.

Another object is to provide an arrangement for manually operating a spring switch which will give a forcible tactful signal to a switchman of the presence of a load on the hand-throw lever.

A further object is to provide an improved safety latch mechanism for the hand-throw lever of a spring switch.

A further object is to provide improved safety mechanism for use in connection with a manually movable member which is required to be positioned under load.

I accomplish these objects of my invention by providing an auxiliary latch in connection with the conventional latch mechanism commonly used in connection with hand-throw levers for switches. The conventional latch consists of a

2

latch member which holds the lever in its normal position, and a latch releasing pedal arrangement which, upon depression of the pedal, removes the latch member from the path of the hand-throw lever. My auxiliary latch is spaced a short distance from the end position of the hand-throw lever, so that the lever can travel a short distance when the main latch is released. The auxiliary latch is connected to the pedal which releases the main latch so that the auxiliary latch is moved into a position to obstruct movement of the lever whenever the main latch is released. The auxiliary latch is arranged so that the lever will be moved forcibly into engagement with it if there is a spring load on the switch when the main latch is released. This movement of the lever gives the switchman a forcible tactful warning of the load on the lever. The auxiliary latch is provided with a depending tongue which engages the lever and prevents release of the auxiliary latch unless the lever is first backed away from the auxiliary latch far enough to disengage the tongue. Since the lever is under considerable load, this backing away movement of the lever can most readily be accomplished by the operator stepping to the end of the lever and assuming a position where all of his body except his hands is clear of the path of movement of the lever. The auxiliary lever is self biased to its unlatched position, so that when the pedal is released and the lever is backed away from the auxiliary latch, the latch moves to its released position so that the movement of the hand-throw lever may be completed. The operator has been warned by this time, so that he will not carelessly release the lever for uncontrolled movement. Furthermore, he is in such a position that he may protect himself against the movement of the lever.

Other objects and characteristic features of my invention will become apparent as the description proceeds.

I shall describe one form of apparatus embodying my invention, and shall then point out the novel features thereof in claims.

In the accompanying drawings, Fig. 1 is a diagrammatic view showing a spring switch and operating mechanism therefor embodying my invention. Fig. 2 is a top plan view of a hand-throw lever provided with my improved latching mechanism. Fig. 3 is a side elevation of my improved latching mechanism, taken on the line III—III of Fig. 2.

Referring to Fig. 1, the reference character 1 generally indicates a railway switch comprising two fixed rails 2 and 3 and two movable rails 4

and 5. The movable rails are fastened together by a front rod 6, a head rod 7, and a tie rod 8, and may be moved to a normal or to a reverse position by means of a switch operating mechanism 9 which is connected with the head rod 7 through the medium of an operating rod 10 and a spring connecting rod 11. When the switch occupies its normal position, in which it is shown in Fig. 1, the movable rail 5 engages the fixed rail 2 and the movable rail 4 is spaced a short distance from the fixed rail 3. When the switch is reversed, however, the movable rail 4 then engages the fixed rail 3, and the movable rail 5 is spaced from the fixed rail 2.

The spring connecting rod 11 may take any of several well-known forms. Such a spring rod must yieldably hold the switch points in whichever extreme position they are moved to by the mechanism 9 with sufficient force to permit facing point moves over the switch without danger of displacement of the points. The spring rod must also yield when a train trails the switch, and thereby allow the train to force the switch points to positions opposite to their initially set positions. One form of spring connecting rod which will accomplish the necessary results is shown and described in Letters Patent of the United States No. 1,976,827, granted to Herbert L. Bone on October 16, 1934, for Railway switch operating apparatus.

The switch operating mechanism 9 may, for example, be similar to that shown and described in Letters Patent of the United States No. 2,184,870, granted to Herbert L. Bone and Kenneth J. J. McGowan on December 26, 1939, for Railway switch operating mechanisms. It is believed that for the purposes of my present invention the following brief description of this mechanism will be sufficient.

The switch operating mechanism 9 includes a motion plate 12 which is arranged to be reciprocated between two extreme positions by means of a hand-throw lever 13 through the medium of a shaft 14 and a gear wheel 15 which cooperates with a rack formed in the motion plate 12. The motion plate 12 moves in stationary guides 16.

A roller 17 is pivotally secured to the underside of the motion plate 12. This roller cooperates with cam faces 18a and 18b formed on an escapement crank 18. The crank 18 rotates on a fixed pivot and carries with it a switch operating arm 19 which is pivotally attached to the free end of the operating rod 10.

As the hand-throw lever 13 is rotated in a counterclockwise direction from the position shown in Fig. 1, the motion plate 12 is moved to the right. The initial movement of plate 12 carries the roller 17 to the right along the cam surface 18a, without causing rotation of escapement crank 18. When the roller 17 reaches the end of cam portion 18a, it enters the generally semi-circular recess 18c of the escapement crank 18, and thereafter its continued movement toward the right causes the crank 18 to rotate counterclockwise (as viewed in Fig. 1) on its shaft, thereby moving the switch operating arm 19 counterclockwise and shifting the switch points from their normal to their reverse positions. After the switch has reached its reverse position, the roller 17 passes out of the recess 18c, and engages the cam surface 18b, thereby holding the escapement crank 18 and the operating rod 10 in their reverse positions.

The switch operating mechanism 9 also includes

a locking plunger 20 which cooperates with a pair of aligned notches 21a in a lock rod 21 secured to the front rod 6 of the switch. The locking plunger is biased by means of a spring 22 to a locking position in which, when the switch occupies its normal position, it will enter the notches 21a in the lock rod 21 and thus lock the switch. Locking plunger 20 is arranged to be moved to an unlocking position prior to any movement of the switch points away from their normal position by the mechanism 9. This may be done by any suitable means, such as that indicated diagrammatically in the drawings by a lug 12a formed on the motion plate and cooperating with a lug 20a on the locking plunger 20. The locking plunger is also arranged to be moved to its unlocking position, prior to any movement of the switch points away from their normal position by a trailing train, through the medium of a suitable lock releasing linkage connected to the tie rod 8 and including a bell crank lever 23, substantially as described in the Bone Patent No. 1,976,827, referred to above.

A safety latch mechanism 24 is provided for holding the hand-throw lever 13 in its normal position. This safety latch mechanism is more completely described in connection with Figs. 2 and 3.

Referring to Figs. 2 and 3, it may there be seen that the safety latch mechanism 24 includes a base casting 25 supported on a mounting plate 26 by means of bolts 27. The upper part of casting 25 is formed to provide an inner jaw 25a and a pair of spaced outer jaws 25b—25c. A recess between the inner and outer jaws receives the hand-throw lever 13. A latch member 28 is pivotally mounted between the outer jaws 25b—25c on a pin 29. A latch releasing member 30 is also pivotally mounted between the outer jaws 25b—25c on a pin 31. The latch member 28 is provided with a depending main latch arm 28a, a depending latch operating arm 28b, and an upstanding auxiliary latch arm 28c. The extremity of the upstanding auxiliary latch arm 28c is provided with a depending tongue 28d. The main latch arm 28a is contoured to engage the inner jaw 25a so as to prevent further counterclockwise rotation of the latch member 28 when the parts are in the position shown in Fig. 3. The latch member 28 is provided with an eye 28e to receive the bail of a padlock when the parts are in the position shown in Fig. 3. The bail of the padlock cooperates with a hook 25d formed on the base casting 25 to prevent clockwise motion of the latch member 28 from the position shown in Fig. 3 when the padlock is in place. The latch member 28 carries a pin 32 which cooperates with the hook 25d to limit the clockwise rotation of latch member 28 when the padlock is removed.

The latch operating arm 28b cooperates with an upstanding arm 30a of the latch releasing member 30. The extremity of arm 28b is provided with a pedal portion 28f, which is used to force the latch member 28 into a position where the padlock bail may be inserted in the aperture 28e.

The latch releasing member 30 is provided with a pedal 30b, and with a stop arm 30c which cooperates with a portion 25e of the base casting 25 to limit rotation of the latch releasing member 30 in a counterclockwise direction.

Operation

With the parts in the position shown in full

lines in the drawings, let it first be assumed that it is desired to move the switch from its normal to its reverse position with no train in the switch, so that there is no spring load on the hand-throw lever 13. In order to release the hand-throw lever from the latching mechanism, the operator first removes the padlock from the aperture 28e, and then depresses the latch releasing pedal 30b. This turns the latch releasing member 30 clockwise. The arm 30a on the member 30 engages the operating arm 28b of the latch member 28 and rotates the latch member clockwise, thereby carrying the main latch arm 28a out of the path of the lever 13 and moving the auxiliary latch arm 28c to the position shown in dotted lines in the drawings, where it is in the path of the lever 13. The operator may now lift the hand-throw lever 13 and move it upwardly until it reaches the dotted line position shown in Fig. 3, where it engages the auxiliary latch arm 28c. In order to move the lever further, he must then release the pedal 30b, so that the latch 28 will tend to return by gravity to the full line position shown in the drawings. However, such a movement of the latch member 28 is now prevented by the tongue 28d. This tongue extends over the side of the lever 13 and prevents the latch member 28 from returning to its released position until the lever 13 is backed away from the auxiliary latch 28c a short distance. The operator must therefore back the lever 13 away from latch 28c a short distance, whereupon the latch member 28 will return to the position wherein the auxiliary latch arm 28c is out of the path of movement of lever 13. Movement of the lever 13 to its reverse position may then be completed by the operator.

Now let it be assumed that the same operation of the hand-throw lever 13 is to be performed, under the conditions existing when a train is trailing the switch and has stopped with a truck in the switch so that the switch points are moved to their reverse positions. Spring 11 is then compressed and applies a strong biasing force to the operating rod 10, tending to rotate the arm 19 and the escapement crank 18 counterclockwise as viewed in Fig. 1. When the parts are in their initial position as viewed in Fig. 1, this biasing force acts through the roller 17 and tends to move the motion plate 12 laterally, which movement is prevented by reactive forces on the guides 16. The biasing force therefore initially applies no torque to the shaft 14 or the hand-throw lever 13.

In order to operate the hand-throw lever 13 under these conditions, the operator removes the padlock and depresses the pedal 30b as before. He then starts to lift the hand-throw lever. As soon as he has lifted the hand-throw lever far enough so that the roller 17 passes off the cam portion 18a of the escapement crank 18 and into the recess 18c, then the biasing force acting on the escapement crank 18 becomes effective to bias the roller 17 and motion plate 12 for movement toward the right, thereby applying a counterclockwise torque to the lever 13. As soon as this happens, this biasing force moves the lever 13 forcibly upward into engagement with the latch 28c. The latch member 28c is so positioned with respect to the switch operating mechanism 9, that the roller 17 moves into the recess 18c shortly before the lever 13 strikes the auxiliary latch arm 28c. This sudden movement of the lever 13 into engagement with the auxiliary latch 28c will be sufficient to warn even the most careless and negligent operator that the hand-

throw lever is subject to a large biasing force, and that he must use care in operating it.

In order to complete the movement of the hand-throw lever 13 to its reverse position, the operator must, as in the previous case, release the pedal 30b and back the lever 13 away from the auxiliary latch 28c. However, the backing of the lever 13 away from auxiliary latch arm 28c now requires the application of a considerable force to oppose the biasing force of the spring 11. The most natural and convenient way for the operator to apply such a large biasing force to the lever 13 is to step around to the end of the lever and bend downwardly over it, placing both hands on the lever and throwing his weight downwardly on his hands. This places the operator in such a position that all of his body except his hands is out of the path of movement of the hand-throw lever. Furthermore, he is in the best position to apply a restraining force to the hand-throw lever 13 throughout the rest of its operating stroke so as to prevent it from moving suddenly.

It should be noted that the position to which the lever 13 must be backed off to release the auxiliary lever 28c is somewhat critical. If the lever 13 is backed away too far, it will engage the main latch arm 28a of the latch member 28, thereby causing the latch member to move clockwise again and restore the auxiliary latch arm 28c to its latching position. The result is that the operator must keep the hand-throw lever 13 under close and careful control at all times during the unlatching phase of its operation. In this way, proper attention on the part of the operator is insured.

Although I have herein shown and described only one form of railway switch operating apparatus embodying my invention, it is understood that various changes and modifications may be made therein within the scope of the appended claims without departing from the spirit and scope of my invention.

Having thus described my invention, what I claim is:

45. 1. Railway switch operating apparatus, comprising a railway switch movable between normal and reverse positions, a manual lever movable between normal and reverse positions, means connecting the lever to the switch including spring 50 means to permit trailing of the switch by a train, a first latch for holding the lever in its normal position, manual means for operating the latch, and an auxiliary latch for limiting the lever movement when the first latch is released to prevent 55 the spring means from suddenly moving the lever to its reverse position when the first latch is operated while a trailing train is in the switch.
55. 2. Railway switch operating apparatus as in claim 1, in which the auxiliary latch limits the 60 lever to a small initial movement, and in which initial movement of the lever by the spring means gives to an operator a tactful signal of the presence of a biasing force on the lever.
60. 3. Railway switch operating apparatus as in claim 1, in which the means for connecting the lever to the switch includes a lost-motion connection which provides a range of movement of the lever at the beginning of its travel from its normal position wherein the lever moves independently of the switch and is not subjected to any biasing force of the spring means, and in which the auxiliary latch becomes effective just after the lever has passed through the said range of lever movement and is subject to the biasing force 70 of the spring means.

4. Railway switch operating apparatus as in claim 1, including means connecting the auxiliary latch to the first latch operating means for concurrent movement therewith so that the auxiliary latch is moved to its latching position concurrently with the release of the first latch.

5. Railway switch operating apparatus as in claim 4, in which the auxiliary latch permits movement of the lever to an intermediate position out of the path of the first latch so that movement of the latch operating means to its latching position after the lever reaches said intermediate position releases the lever from both latches.

6. Railway switch operating apparatus as in claim 1, in which the auxiliary latch has a tongue which engages the lever and prevents release of the auxiliary latch except by a movement of the lever toward its normal position.

7. The combination with a railway switch movable between normal and reversed positions, a manual lever movable between normal and reversed positions, means connecting the lever to the switch including spring means to permit trailing of the switch by a train, latch means for holding the lever in its normal position and manual means for releasing the latch means, of an auxiliary latch for limiting the lever movement when the latch means is released so that operation of the lever by the spring means during such limited movement gives to an operator a tactual signal of the presence of a biasing force on the lever.

8. The combination with a railway switch movable between normal and reversed positions, a manual lever movable between normal and reversed positions, means connecting the lever to the switch including spring means to permit trailing of the switch by a train and lost-motion means to provide a range of lever movement at the beginning of its stroke from normal to reversed position wherein the lever moves independently of the switch and is not subjected to any biasing force of the spring means, latch means for holding the lever in its normal position and manual means for releasing the latch means, of an auxiliary latch effective when the latch means is released to limit the lever movement to a point just beyond said range so that the spring means is effective when the lever is operated while a trailing train is in the switch to move the lever a short distance before it strikes the auxiliary latch, thereby giving to the operator a tactual signal of the presence of a biasing force on the lever.

9. Manual operating apparatus, comprising a device subject at times to a biasing force, a manually movable member, a connection between the member and the device, latch means for holding the member in a selected position, manual means for operating the latch means, and an auxiliary latch for limiting the movement of the member when the latch means is released so that a biasing force on the device will give a tactual signal of its presence to the operator by moving the member until it strikes the auxiliary latch.

10. Manual operating apparatus as in claim 9, including means connecting the auxiliary latch to the latch operating means for concurrent movement therewith so that the auxiliary latch is released, and moves to its unlatched position as the latch means moves to its latching position.

11. Manual operating apparatus as in claim 9, including a tongue on the auxiliary latch which engages the movable member and prevents re-

lease of the auxiliary latch unless the movable member is first backed away.

12. Manual operating apparatus as in claim 11, in which the auxiliary latch is biased to its released position so that when the manual latch operating means is released and the movable member is backed away from the auxiliary latch the latter returns to its released position.

13. Manual operating apparatus comprising a manually movable member, latch means for holding the member in a selected position, manual means for operating the latch means, and an auxiliary latch for limiting the movement of the member when the latch means is released so that if the member is loaded a tactual signal of the presence of the load will be given to the operator by the initial movement of the member into engagement with the auxiliary latch.

14. Manual operating apparatus as in claim 13, including means connecting the auxiliary latch to the latch operating means for concurrent movement therewith so that the auxiliary latch moves to its latching position as the latch means is released and moves to its unlatched position as the latch means moves to its latching position, and a tongue on the auxiliary latch which engages the movable member and prevents release of the auxiliary latch unless the movable member is first backed away; in which the auxiliary latch is biased to its released position so that when the manual latch operating means is released and the movable member is backed away from the auxiliary latch the latter returns to its released position; and, in which the auxiliary latch is spaced from the latch means sufficiently so that the member may be backed away far enough to release the auxiliary latch without moving into a position where it will be engaged by the latch means.

15. Railway switch operating apparatus, comprising a railway switch movable between normal and reverse positions, a hand-throw lever movable between normal and reverse positions, means connecting the lever to the switch including spring means to permit trailing of the switch by a train, latch means for the hand-throw lever including a support for the lever in its normal position, first and second jaw means on the support forming between them an aperture for receiving the lever, said first jaw means comprising a pair of spaced jaws, first and second pivot pins carried by the spaced jaws and extending between them, a latch member rotatable on said first pin and having first and second latch arms and an operating arm, and a latch operating member rotatable on the second pin and having a first pedal arm and a second arm for engaging the operating arm of the latch member to rotate said member, said latch member being biased by gravity to a normal position in which said first latch arm lies between said jaw means and prevents movement of the lever from its normal position, said latch member also being movable by operation of said pedal arm to a second position wherein the first latch arm is removed from between the jaw means and the second latch arm lies in the path of the lever to limit its movement toward said second position.

16. Railway switch operating apparatus, comprising a railway switch movable between normal and reverse positions, a hand-throw lever movable between normal and reverse positions, means connecting the lever to the switch including spring means to permit trailing of the switch by a train, latch means for the hand-throw lever

including a support for the lever in its normal position, first and second jaw means on the support forming between them an aperture for receiving the lever, said first jaw means comprising a pair of spaced jaws, first and second pivot pins carried by the spaced jaws and extending between them, a latch member rotatable on said first pin and having first and second latch arms and an operating arm, and a latch operating member rotatable on the second pin and having a first pedal arm and a second arm for engaging the operating arm of the latch member to rotate said member, said latch member being biased by gravity to a normal position in which said first latch arm lies between said jaw means and prevents movement of the lever from its normal position, said latch member also being movable by operation of said pedal arm to a second position wherein the first latch arm is removed from between the jaw means and the second latch arm lies in the path of the lever to limit its movement toward said second position, said second latch arm having a tongue which engages the lever and prevents removal of the second latch arm from the path of the lever unless the lever is first moved back toward its normal position far enough to clear said tongue.

17. A lever latch stand for use in connection with a lever movable to and from a normal position, comprising a first latch biased to a latching position wherein it holds the lever in its normal position and movable to a released position, an auxiliary latch connected to the first latch for concurrent movement therewith and effective when the first latch moves to its released position to obstruct the path of movement of the lever at a predetermined distance away from its normal position, and manually operable means for moving said first latch to its released position in opposition to its bias.

18. A lever latch stand for use in connection with a lever movable to and from a normal position and at times subject to a load tending to move the lever away from said normal position, said latch stand comprising a first latch biased to a latching position wherein it holds the lever in its normal position and movable therefrom to

a released position wherein it permits movement of the lever away from its normal position, an auxiliary latch connected to the first latch for concurrent movement therewith and effective when said first latch is in its released position to obstruct the path of movement of the lever a predetermined distance away from its normal position, said auxiliary latch being moved out of the path of the lever concurrently with movement of the first latch to its latching position, and manually operable means for moving said first latch to its released position in opposition to its bias so that the lever may be moved through said predetermined distance into engagement with said auxiliary latch, said auxiliary latch being releasable by disengagement of the lever therefrom with concurrent release of said manually movable means.

19. A lever latch stand for use in connection with a lever movable to and from a normal position and at times subject to a load tending to move the lever away from said normal position, said latch stand comprising a support for the lever in its normal position, first and second jaw means on the support forming between them an aperture for receiving the lever, said first jaw means comprising a pair of spaced jaws, first and second pivot pins carried by the spaced jaws and extending between them, a latch member rotatable on said first pin and having first and second latch arms and an operating arm, and a latch operating member rotatable on the second pin and having a first pedal arm and a second arm for engaging the operating arm of the latch member to rotate said member, said latch member being biased by gravity to a normal position in which said first latch arm lies between said jaw means and prevents movement of the lever from its normal position, said latch member also being movable by operation of said pedal arm to a second position wherein the first latch arm is removed from between the jaw means and the second latch arm lies in the path of the lever to limit its movement toward said second position.

Certificate of Correction

Patent No. 2,492,374

December 27, 1949

GEORGE W. BAUGHMAN

It is hereby certified that error appears in the printed specification of the above numbered patent requiring correction as follows:

Column 7, line 70, after the word "latch" insert *moves to its latching position as the latch means;*

and that the said Letters Patent should be read with this correction therein that the same may conform to the record of the case in the Patent Office.

Signed and sealed this 25th day of April, A. D. 1950.

[SEAL]
